UNITED STATES PATENT OFFICE

2,661,405

SAFETY DOWN LIMIT SWITCH FOR
CABLE HOISTSJames A. Western, Detroit, Mich., assignor to
Detroit Hoist and Machine Company, Detroit,
Mich., a corporation of Michigan

Application July 13, 1950, Serial No. 173,621

1 Claim. (Cl. 200—47)

1

This invention relates to cable hoists, and more particularly to a safety down limit switch for a cable hoist.

Normally cable hoists of this type are provided with an uplimit safety switch to stop the hoist motor automatically when the hoisting block reaches its uppermost position. When the hoist was operated by a manual switch to control unwinding of the cable, in the event that the operator did not stop the downward movement of the hoisting block it would automatically begin to rewind after the drum had completely unwound the cable thereon. By inadvertent or careless failure to deenergize the electric motor controlling the downward movement of the hoist block, the cable would automatically rewind again raising the block to its uppermost position. The conventional operation of the up limit switch by the block when it reached its uppermost position would be ineffective to deenergize the hoist motor as long as the remote control manual down switch was active. This would result in continued upward movement of the block causing the cable to break with consequent damage to property and endangering of the lives of others.

It is the principal object of the present invention to provide a safety down limit switch which would cause automatic deenergization of the hoist motor at the completion of the unwinding of the cable from the drum.

It is the further object of the present invention to provide a safety limit switch which is normally connected in the electrical circuit to the hoist operating motor and which is adapted for operative engagement with the cable as it starts to rewind for automatically breaking said electrical circuit and stopping the motor.

These and other objects will be seen from the following specification and claim in conjunction with the appended drawings in which:

Fig. 1 is a side elevational view of a portion of the cable hoist shown in Fig. 4 with the rotatable drum thereof sectioned for illustration.

Fig. 2 is a bottom plan view of the down safety limit switch and its mounting and actuating mechanism, shown on an enlarged scale.

Fig. 3 is an elevational view thereof viewed from the upper end of Fig. 2.

Fig. 4 is an elevational view of the hoist with the safety down limit switch mounted thereunder; and

Fig. 5 is a wiring diagram showing the hoist motor, the load lines adapted for connection thereto, the manual control switches for operating additional switch mechanism for regulating the connections of the load lines with the hoist controlling motor for energizing the same and determining its direction of rotation.

2

It will be understood that the above drawings illustrate merely a preferred embodiment of the invention, and that other embodiments are contemplated within the scope of the claims hereinafter set out.

The hoist mechanism shown in Figs. 1 and 4 includes the hoist housing 10' which includes the electric reversible motor 27 and the rotary cable winding drum 14 which is connected to the shaft 27' of said motor in any conventional fashion such as by suitable pulleys and a connecting belt or by sprockets upon the respective shafts of the motor and drum with a chain interconnecting the same.

The driving connection between motor 27 and the rotatable drum 14 is conventional, and for this reason further illustration of this drive is believed unnecessary. A suitable inverted hook 29 projects from the upper portion of the hoist housing providing a means for supporting the same.

The flexible cable 12 is anchored at one end at 13 within the housing 10' and is looped downwardly with its lowermost portion supporting the load block 25 with depending hook 26, and with the other end of the cable 12 joined to the rotatable drum 14 at 15 as shown in Fig. 1.

It will be noted that in Fig. 4 the cable 12 is shown fully wound upon the drum 14, whereas in Fig. 1 the cable has been fully unwound and has begun to be rewound upon the drum 14.

A down safety limit switch construction is provided secured to the under side of the hoist 10' with the movable portion thereof in spaced relation to the cable 12 while it is wound upon the drum 14 but which is engageable with the cable as shown in Fig. 1 after the same has been fully unwound and has just begun to rewind upon said drum.

The down safety limit switch construction includes the rectangular mounting plate 1 which is shown in enlarged scale in Fig. 2 and which is provided with transverse openings 33 by which the said plate is secured to the under side of the hoist as by the bolts 34 shown in Fig. 1.

45 A pair of spaced downwardly depending flanges 2 and 3 extend from the forward portion of plate 1, which flanges are provided with openings to receive the spaced horizontally extending bolts 4 and 5 which are secured thereto by the lock nuts 6 and 7 in the manner illustrated in Fig. 2.

Limit switch actuating bar 10 is apertured at its opposite ends for mounting slidably upon the two bolts 4 and 5 with the outward positioning of said plate limited by the heads 11 upon said bolts. Coiled springs 8 and 9 are mounted around the bolts 4 and 5 and are interposed between lock nuts 7 and the inner surface of the plate 10 for

normally maintaining said plate in its outward position as shown in Fig. 2.

It will be noted that the plate 10 is arranged normally of the cable 12 and in spaced relation thereto when the cable is wound upon the drum 14 as shown in Fig. 4; however the plate 10 will be engaged by the cable 12 when the same has been completely unwound and begins to rewind upon the drum 14 in the manner illustrated in Fig. 1. Inward movement of the plate 10 will be caused by this operative engagement of the cable therewith for actuating the limit switch plunger 17 as shown in Fig. 2.

The down safety limit switch is generally indicated at 16 and is supported upon the under side of the plate 1 as by the bolts 16' and their nuts as illustrated in Figs. 2 and 3.

In the manner illustrated in Fig. 5 the down safety limit switch 16 is connected in the electrical circuit which controls rotation of the electric motor 27 to cause unwinding of the cable drum 14. The down limit switch 16 is normally closed but includes the reciprocal plunger 17 which is adapted to open said limit switch, the outer end of said plunger being in engagement with the movable control plate 10.

As shown in dotted lines in Fig. 4 there is provided a conventional up safety limit switch 18 which is positioned within the hoist housing 10' and which is engageable by the block 25 in its uppermost position for automatically deenergizing the electric motor 27 in its driving of the upward winding movement of the cable drum 14.

This up safety limit switch is conventional and is interposed in the electrical circuit as shown in Fig. 5 for automatically deenergizing the electric motor 27 when the hoist block 25 has reached a predetermined uppermost position.

It is apparent that in the absence of the present down safety limit switch, if the motor was not manually deenergized when the cable was completely unwound from the drum, said cable would begin to rewind causing elevation of the block 25 until the cable broke because actuation of this up safety limit switch would not in this case deenergize said motor.

As illustrated in Figs. 4 and 5 there is provided a remote control station or housing 30 which includes a pair of push buttons or switch controls 31 and 32. Button 31 being adapted to control or energize the motor 27 for causing upward movement of the block 25 whereas button 32 is adapted to reverse the operation of the motor 27 to cause downward movement of the block 25.

As shown in Fig. 5 button 31 is joined to control plate 29 for closing the circuit between contact points 21 and 22 whereas the control plate 19 is connected to the push button 32 for closing the circuit between contact points 23 and 24.

Generally the push buttons 31 and 32 are adapted for effecting energization of the electric motor 27 for rotating the same in one direction or another. It is seen that safety limit switch 18 is arranged in the electrical circuit associated with push button 31 for controlling upward movement of the block 25 and will be automatically opened opening said circuit if and when the block 25 rises above a predetermined position to engage said up limit switch designated in Fig. 4.

Upon the other hand the down safety limit switch 16 is arranged in the electrical circuit to the motor 27 which is associated with the down push button 32 in Fig. 5.

For the purpose of the present application the

down safety limit switch construction is actuated by engagement of the cable 12 with the control plate 10 which in turn depresses the limit switch plunger 17, in effect opening the limit switch 16 or the circuit in which it is connected for deenergizing the motor when it is being operated for lowering the cable block 25.

As the motor 27 is reversible it is necessary that a relay switch mechanism be employed which is adapted to change and reverse the electrical connections between the power lines L1, L2 and L3 and the terminals of motor 27.

While the particular mechanism for the relay forms no part of the present invention the electrical connections therefor are diagrammatically indicated in Fig. 5, with the relay switch housing being generally indicated by the numeral 28. Naturally various types of electrical connections could be employed responsive to the push buttons 31 and 32 for effecting reversals in the direction of rotation of the motor 27, and it is understood that the illustration of connections within the housing 28 of Fig. 5 shows one way of accomplishing this reversal. Push button 31 through plate 26 and contacts 21 and 22 and the connected lead wires are adapted to energize the magnetic control 35 for the relay switch 35' to cause rotation of motor 27 in such direction as to cause winding of the cable 12 on the drum 14.

On the other hand push button 32, plate 19 and contacts 23 and 24 are adapted to energize the magnetic control 36 which regulates the relay switch 36' to establish a reversed electrical connection to motor 27 to reverse its direction of rotation.

Having described my invention reference should now be had to the claim which follows for determining the scope thereof.

I claim:

40 In a safety device for a cable hoist, a mounting plate adapted to be secured upon the underside of said hoist adjacent its cable, a normally closed limit switch mounted upon said plate, a movable limit switch actuating plunger pin projecting therefrom, a pair of spaced stationary supports 45 projecting from said mounting plate, a flat plate of rectangular cross-section transversely apertured to slidably receive said supports and movably mounted thereon adjacent said switch and normally engaging said plunger pin, arranged 50 transversely of and in spaced relation to said cable upon unwinding thereof and engageable by said cable as it rewinds for opening said limit switch, means on said stationary supports limiting the outward positioning of said plunger 55 engaging plate, and coiled springs on said supports interposed between said mounting plate and said plunger engaging plate normally urging said plunger engaging plate into its outward non-actuating position.

60 JAMES A. WESTERN.
